CONTROL CIRCUIT AND ACTUATING MECHANISM FOR A COAXIAL SWITCH

William R. Elliott, Bellevue, Wash., assignor to Thompson Products, Inc., Cleveland, Ohio, a corporation of Ohio

Application January 26, 1953, Serial No. 333,106

9 Claims. (Cl. 318—267)

This invention relates to a rotary switch actuating mechanism, and more particularly to an actuating mechanism for moving the rotor of a coaxial switch to one or more preselected positions.

Many of the actuating mechanisms adapted for rotary coaxial switches which have been developed in the past have been of the solenoid operated, ratchet type which provides step-by-step movement of the coaxial switch rotor to one or more preselected positions. Many advantages have been found to result from the utilization of an electric motor to drive a rotary coaxial switch, particularly ruggedness and reliability in use.

It is, therefore, an object of the present invention to provide a novel actuating mechanism for a rotary coaxial switch which is driven by means of a continuously rotatable driving member rather than by means of a step-by-step driving member.

When a continuously rotating driving member, such as the rotor of an electric motor, is utilized to move a coaxial switch rotor to a preselected position, the angular momentum of the rotor of the electric motor, after the electric motor is deenergized, tends to drive the coaxial switch rotor past the preselected position.

If a detent is applied to a switch driven by an electric motor, the angular momentum of the rotary driving member combined with the acceleration contributed by the detent means prior to a selected position tends to drive the switch rotor past the preselected position, and the retarding action of the detent beyond the preselected position is often inadequate to stop the switch rotor and return it to the preselected position.

It is, therefore, a further object of the present invention to provide novel means for rendering the angular momentum of the rotary driving member ineffective to drive the switch rotor beyond the operative range of a detent means, or other means acting to position the switch rotor in the preselected position.

Another object of the present invention is to provide novel indexing mechanism for a coaxial switch in which the driving means is electrically braked and the brake is automatically released when the rotor has been completely stopped.

It is a still further object of the present invention to provide novel means for applying a retarding torque to the rotary driving member to overcome its angular momentum adjacent a selected switching position.

Other novel features which are believed to be characteristic of my invention are set forth with particularity in the appended claims. My invention itself, however, both as to its organization, manner of construction and method of operation, together with further objects and advantages thereof, may be thus understood by reference to the following description taken in connection with the accompanying drawings, in which:

Figure 1 is a diagrammatic view partly in section of an actuating mechanism embodying the novel principles and teachings of the present invention as it would be applied to a single pole, double throw rotary coaxial switch;

Figure 2 is a fragmentary transverse section view taken substantially along the line II—II of Figure 1;

Figure 3 is a longitudinal sectional view taken substantially along the line III—III of Figure 2; and

Figure 4 is a schematic diagram indicating the control system for the motor.

The present invention is particularly adapted for use with a rotary coaxial switch having a rotor which is designed to be rotated into one or more preselected positions to complete one or more circuits. It will be readily appreciated that in a coaxial-type switch much more precise positioning of the switch rotor is required than in the ordinary switch. It is the particular problems which are met in the coaxial-type switch to which the present invention is particularly directed, and the actuating mechanism according to the present invention is, therefore, illustrated as it might be applied to a rotary coaxial switch, by way of example, but not with the intention of limiting the invention thereto.

The actuating mechanism of the present invention is also particularly adapted for use with a control system for selectively indexing the switch rotor to one of a plurality of preselected switching positions. The invention is, therefore, illustrated as it might be employed with such an index and control system by way of example and not by way of limitation.

Referring particularly to Figure 1, by way of example, a single pole, double throw rotary coaxial switch 10 is operated by an actuating mechanism generally designated by the reference numeral 11. The rotary switch 10 comprises stationary switch body 12 and a switch rotor 13 rotatably mounted therein.

The switch rotor 13 has an inner conductor elbow 14 having a reduced diameter pin 15 at one end extending axially of said switch rotor for continuous contact with prongs 17 of the inner conductor 18 extending axially of the rotor and axially of the main fitting 19 of the switch. The inner conductor elbow 14 is carried in the rotor 13 and is insulated from the metallic plug 20 of the rotor by means of insulation 21. The inner conductor 18 of the main fitting 19 is centered axially of fitting 19 by means of insulation 22. The switch rotor 13 is turned to selectively establish a circuit between the inner conductor 18 of the main fitting and the inner conductors 23, 24 of the branch fittings 25 and 26. Each of the coaxial fittings 19, 25 and 26 may be provided with suitable means for connection to coaxial cables, as external threads (not shown). It will be understood that the interior walls 27, 28 and 29 of the coaxial fittings 19, 25 and 26 afford outer conductors for connection with the outer conductors of coaxial cables connected to the fittings, and that the interior wall 30 of the elbow passage in the metallic plug 20 serves to establish continuity between the outer conductor 27 and the outer conductors 28 and 29 of the branch fittings 25 and 26.

The switch rotor 13 is directly connected to a shaft 32 which is adapted to be driven by means of a rotary driving member such as the rotor of an electric motor 33. The drive connections between the motor 33 and the shaft 30 include the motor shaft 34, pinion 35, driving gear 36, shaft 37, associated pinion 38, driving gear 39 and shaft 40.

In order to accurately position the switch rotor 13 in preselected switching position, a detent mechanism indicated generally by reference numeral 41 is provided. In general, the switch detent mechanism defines a plurality of central positions which correspond with the desired predetermined switching positions of the rotor and an effective range of angular positions on either side of each central position in which the detent mechanism is operative to move the switch rotor to the central position desired.

By way of definite example, the detent may have an overall range of 30° , with a range in advance of the predetermined switching position of 15° and a range beyond the predetermined switching position of 15° . By way of example, this range of detent action may be accomplished by means of a detent gear 42 which is controlled by means of a pair of opposed arms 43 and 44 illustrated as being pivotally mounted on the coaxial switch housing 12 by means of bolts 45.

The details of this mechanism are described in my copending application entitled "Rotary Coaxial Switch Actuating Mechanism," Serial No. 259,979, filed December 5, 1951, and assigned to the same assignee as the present invention.

As also described in my above mentioned copending application, a "sloppy" coupling indicated generally by the reference numeral 50 is provided between the shafts 32 and 40. This coupling is designed to allow some free play between the action of the switch detent 41 and the motor driving system for the shaft 40. The coupling permits the detent mechanism 41 to center the rotor shaft 32 in its proper position after the shaft 40 has been stopped by means of the braking mechanism which will hereinafter be described.

For disconnecting the motor reverse winding which is utilized to brake the motor, as will hereinafter be described, a switch 55 is utilized which is associated with the shaft 40. The switch comprises a microswitch 56, Figure 2, connected in series with conductors 57 and 58 and having an actuating button 60 for opening the circuit in normal projected position, and for closing the circuits when depressed. The button 60 is controlled by an operating lever 61 loosely carried by the shaft 40 for movement from a lower position abutting the stop 63, Figure 2, to the upper position shown in solid outline in Figure 2 wherein the edge of the lever 61 contacts the button 60 to depress the same. When the shaft 40 is rotating counterclockwise as seen in Figure 2, the lever 61 is lifted to its actuated position by means of friction coupling disks 65 and 66 which are fixed in grooves in the shaft 40 and rotate therewith and have annular end faces 69 and 70 bearing on opposite sides of the lever 61 to urge the lever to turn with the shaft 40. It will be understood that the disks 65 and 66 are of resilient material and are so positioned as to be tensioned to urge the annular faces 69 and 70 against the opposed surfaces of the lever 61. Thus when the shaft is turning counterclockwise, the lever arm 61 will be in the switch actuating position shown in Figure 2, while when the shaft rotated counterclockwise, the lever arm 61 will be moved against the stop 63 to open the motor reversing circuit.

The operation of the control circuit will now be readily understood by reference to Figure 4. In Figure 4, the motor armature is represented at 73, and the motor is provided with a split series field winding including windings 74 and 75, the winding 74 being arranged to drive the shaft 40 in the counterclockwise direction as seen in Figure 2, while the winding 75 is arranged to drive the shaft 40 in the clockwise direction and will be termed the reverse winding of the motor.

The wafer switch 80 shown mounted on the motor shaft 32 in Figure 1 includes rotor sections 81 and 82 which turn with the shaft 32 by virtue of the rectangular slots 83 and 84 interlocked with a flattened portion of the shaft 32 as indicated in Figure 4. Voltage may be supplied to the control circuit by means of a pair of supply lines 85 and 85', and the voltage may be supplied between the common conductor 87 and conductor 88 or 88' by any suitable selector means, such as suitable jacks connected to the three conductors and plugs connected with the respective supply lines, one plug being inserted in the jack for conductor 87 and the other plug being selectively connected with the jack for conductor 87 or 88', or alternatively as illustrated, conductor 87

may be electrically connected with one of the supply lines 85' while a selector switch 86 selectively connects the other supply line 85 with line 88 or 88'. When a supply voltage is applied between common conductor 87 and conductor 88 the motor is driven in the forward direction through conductor 89, stationary contact 90, rotor 81, stationary contact 91, conductor 92, series winding 74, armature 73, to conductor 87. The shaft 40 is now turned in the counterclockwise direction, and the lever 61 actuates the button 60 of microswitch 56 to close the switch 55, Figure 4. When the lobe 94 of rotor 82 of wafer switch 80 reaches the stationary contact 97, and the gap 98 in the rotor 81 reaches the stationary contact 90, the forward winding 74 is deenergized, and the reverse winding 75 is energized through conductor 88, conductor 100, stationary contact 97, rotor lobe 94, stationary contact 101, conductor 57, switch 55, conductor 58, reverse winding 75, armature 73 and conductor 87. The braking action is then exerted on the armature 73 by the reverse winding 75 to bring the shaft 40 to a stop adjacent a selected switching position, in this case with the rotor elbow 14 in registry with the inner conductor 24 of the branch terminal 26. When the armature has completely stopped rotating in the counterclockwise direction and begins to rotate in the clockwise direction due to the reverse winding 75, the lever 61 is moved away from the button 60 to open the microswitch 55 and deenergize the reverse winding 75. It will be understood that the detent means 41 is then free to exactly position the switch rotor in its left hand switching position by virtue of the sloppy coupling 50. The rotors 81 and 82 are illustrated in Figure 4 in positions corresponding to the position of the rotor in Figure 1 at its right hand station. The circuit operation for indexing the rotor to the right hand position shown in Figure 1 is the same as that described hereinabove and need not be specifically described. Corresponding primed reference numerals have been applied to the conductors which are connected to the supply lines to index the switch to its right hand position.

While I have shown a particular embodiment of my invention, it will, of course, be understood that I do not wish to be limited thereto, since many modifications may be made, and I, therefore, contemplate by the appended claims to cover all such modifications as fall within the true spirit and scope of my invention.

I claim as my invention:

1. Indexing mechanism for selectively positioning a rotor with respect to first and second surrounding stations, comprising a motor, first and second energizing circuits for said motor, indexing means driven by said motor and controlling said first and second motor energizing circuits, said indexing means being operative to open said first and second motor energizing circuits when the rotor is in the vicinity of said first and second stations respectively, first and second braking circuits for said motor, rotary switch means driven by said motor and controlling said first and second braking circuits, said switch means being operative to close said first braking circuit when said rotor has angularly moved to a preselected relative position with respect to said first station and being operative to close said second braking circuit when said rotor has angularly moved to a preselected relative position with respect to said second station, and selector means selectively accommodating energization of said first and second motor energizing circuits.

2. Indexing mechanism for selectively positioning a rotor with respect to first and second surrounding stations, comprising a motor, first and second energizing circuits for said motor, indexing switch means driven by said motor and controlling said first and second motor energizing circuits, said indexing switch means being operative to open said first and second motor energizing circuits when the rotor is in the vicinity of said first and second stations respectively, first and second reverse energizing circuits

for said motor, rotary switch means driven by said motor and controlling said first and second motor reverse energizing circuits, said switch means being operative to close said first and second motor reverse energizing circuits when said rotor has angularly moved to a preselected relative position with respect to said first and second stations respectively, and selector means selectively accommodating energization of said first motor energizing and reverse energizing circuit and said second motor energizing and reverse energizing circuit.

3. Indexing mechanism for selectively positioning a rotor with respect to first and second surrounding stations, comprising a motor, first and second energizing circuits for said motor, indexing switch means driven by said motor and controlling said first and second motor energizing circuits, said indexing switch means being operative to open said first and second motor energizing circuits when the rotor is in the vicinity of said first and second stations respectively, first and second reverse energizing circuits for said motor, rotary switch means driven by said motor and controlling said first and second motor reverse energizing circuits, said switch means being operative to close said first and second motor reverse energizing circuits when said rotor has angularly moved to a preselected relative position with respect to said first and second stations respectively, further switch means in the motor reverse energizing circuits maintained closed by continuous rotation of the motor in the forward direction but opening upon reverse rotation of said motor, and selector means selectively accommodating energization of said first motor energizing and motor reverse energizing circuits and said second motor energizing and motor reverse energizing circuits.

4. Indexing mechanism for selectively positioning a rotor with respect to first and second surrounding stations, comprising a motor, a shaft driven by said motor and driving said rotor and having an indexing member thereon, first and second stationary indexing contacts cooperating with said indexing member, first and second motor energizing circuits including respectively said first and second indexing contacts and said indexing member, a braking switch member on said shaft, first and second stationary braking contacts cooperating with said braking member, first and second braking circuits for said motor including respectively said first and second braking contacts and said braking member, said indexing member having non-conducting means for interrupting said first and second motor energizing circuits when the rotor is in the vicinity of said first and second stations respectively, and said braking member closing said first and second braking circuits contemporaneously with the opening of said first and second motor energizing circuits respectively, and selector means selectively accommodating energization of said first motor energizing and braking circuits and said second motor energizing and braking circuits.

5. Indexing mechanism for selectively positioning a rotor with respect to first and second surrounding stations of a coaxial switch, comprising a rotor shaft in driving connection with said rotor, a motor shaft in driving connection with said motor shaft, indexing switch means including an indexing member on said rotor shaft and rotatable therewith and a pair of arcuately spaced stationary indexing contacts disposed about said rotor shaft and cooperating with said indexing member, said indexing member having a non-conducting portion for successively isolating said first and second stationary contacts as said rotor shaft is rotated, braking switch means including a braking member on said rotor shaft and rotatable therewith and first and second braking contacts disposed arcuately about said rotor shaft and cooperating with said braking member, said braking member being operative to successively make contact with said first and second contacts as said rotor shaft is rotated, first and second motor energizing circuits including respectively said first and second indexing contacts and said indexing member for en-

ergizing said motor to drive said rotor in the forward direction, first and second motor braking circuits including respectively said first and second braking contacts and said braking member for applying a braking force to said motor shaft, the respective stationary indexing and braking contacts being arranged with respect to said rotor shaft to contemporaneously deenergize the selected motor-energizing circuit and to energize the corresponding motor braking circuit to selectively position the rotor at the first and second stations, and selector means selectively accommodating energization of said first motor energizing and braking circuits and said second motor energizing and braking circuits.

6. Indexing mechanism for selectively positioning a rotor with respect to first and second surrounding stations of a coaxial switch, comprising a rotor shaft in driving connection with said rotor, a motor shaft in driving connection with said rotor shaft, a motor in driving connection with said motor shaft, indexing switch means including an indexing member on said rotor shaft and rotatable therewith and a pair of arcuately spaced stationary indexing contacts disposed about said rotor shaft and cooperating with said indexing member, said indexing member having a non-conducting portion for successively isolating said first and second stationary contacts as said rotor shaft is rotated, braking switch means including a braking member on said rotor shaft and rotatable therewith and first and second braking contacts disposed arcuately about said rotor shaft and cooperating with said braking member, said braking member being operative to successively make contact with said first and second contacts as said rotor shaft is rotated, first and second motor energizing circuits including respectively said first and second indexing contacts and said indexing member for energizing said motor to drive said rotor in the forward direction, first and second motor braking circuits including respectively said first and second braking contacts and said braking member for applying a braking force to said motor shaft, the respective stationary indexing and braking contacts and said braking member for applying a braking force to said motor shaft to contemporaneously deenergize the selected motor-energizing circuit and to energize the corresponding motor braking circuit to selectively position the rotor at the first and second stations, switch means having contacts in said motor braking circuits maintained closed by continuous rotation of said motor shaft in the forward direction and opening upon reverse movement of said motor shaft, and selector means selectively accommodating energization of said first motor energizing and motor braking circuits and said second motor energizing and motor braking circuits.

7. Indexing mechanism for selectively positioning a rotor with respect to first and second surrounding stations of a coaxial switch, comprising a rotor shaft in driving connection with said rotor, a motor shaft in driving connection with said rotor shaft, a motor in driving connection with said motor shaft, indexing switch means including an indexing member on said rotor shaft and rotatable therewith and a pair of arcuately spaced stationary indexing contacts disposed about said rotor shaft and cooperating with said indexing member, said indexing member having a non-conducting portion for successively isolating said first and second stationary contacts as said rotor shaft is rotated, braking switch means including a braking member on said rotor shaft and rotatable therewith and first and second braking contacts disposed arcuately about said rotor shaft and cooperating with said braking member, said braking member being operative to successively make contact with said first and second contacts as said rotor shaft is rotated, first and second motor energizing circuits including respectively said first and second indexing contacts and said indexing member for energizing said motor to drive said rotor in the forward direction, first and second motor braking circuits including respectively said first and second braking contacts and said braking member for applying a braking

force to said motor shaft, the respective stationary indexing and braking contacts being arranged with respect to said rotor shaft to contemporaneously deenergize the selected motor-energizing circuit and to energize the corresponding motor braking circuit to selectively position the rotor at the first and second stations, switch means having contacts in said motor braking circuits maintained closed by continuous rotation of said motor shaft in the forward direction and opening upon reverse movement of said motor shaft, a sloppy coupling between said motor shaft and said rotor shaft to accommodate limited reverse rotation of said motor shaft without corresponding rotation of said rotor shaft, and selector means selectively accommodating energization of said first motor energizing and motor braking circuits and said second motor energizing and motor braking circuits.

8. Indexing mechanism for selectively positioning a rotor with respect to first and second surrounding stations of a coaxial switch, comprising a rotor shaft in driving connection with said rotor, a motor shaft in driving connection with said rotor shaft, a motor in driving connection with said motor shaft, indexing switch means including an indexing member on said rotor shaft and rotatable therewith and a pair of arcuately spaced stationary indexing contacts disposed about said rotor shaft and cooperating with said indexing member, said indexing member having a non-conducting portion for successively isolating said first and second stationary contacts as said rotor shaft is rotated, braking switch means including a braking member on said rotor shaft and rotatable therewith and first and second braking contacts disposed arcuately about said rotor shaft and cooperating with said braking member, said braking member being operative to successively make contact with said first and second contacts as said rotor shaft is rotated, first and second motor energizing circuits including respectively said first and second indexing contacts and said indexing member for energizing said motor to drive said rotor in the forward direction, first and second motor braking circuits including respectively said first and second braking contacts and said braking member for applying a braking force to said motor shaft, the respective stationary indexing and braking contacts being arranged with respect to said rotor shaft to contemporaneously deenergize the selected motor-energizing circuit and to energize the corresponding motor braking circuit to selectively position the rotor at the first and second stations, switch means having contacts in said motor braking circuit maintained closed by continuous rotation of said motor shaft in the forward direction and opening upon reverse movement of said motor shaft, a sloppy coupling between said motor shaft and said rotor shaft to accommodate limited reverse rotation of said motor shaft without corresponding rotation of said rotor shaft, detent means acting on said rotor shaft to establish precise angular positions of said ro-

5 10 15 20 25 30 35 40 45 50 55

tor at said first and second stations, and selector means selectively accommodating energization of said first motor energizing and braking circuits and said second motor energizing and braking circuits.

9. Indexing mechanism for selectively positioning a rotor with respect to first and second surrounding stations of a coaxial switch, comprising a rotor shaft in driving connection with said rotor, a motor shaft in driving connection with said rotor shaft, a motor in driving connection with said motor shaft, indexing switch means including an indexing member on said rotor shaft and rotatable therewith and a pair of arcuately spaced stationary indexing contacts disposed about said rotor shaft and cooperating with said indexing member, said indexing member having a non-conducting portion for successively isolating said first and second stationary contacts as said rotor shaft is rotated, braking switch means including a braking member on said rotor shaft and rotatable therewith and first and second braking contacts disposed arcuately about said rotor shaft and cooperating with said braking member, said braking member being operative to successively make contact with said first and second contacts as said rotor shaft is rotated, first and second motor energizing circuits including respectively said first and second indexing contacts and said indexing member for energizing said motor to drive said rotor in the forward direction, first and second motor braking circuits including respectively said first and second braking contacts and said braking member for applying a braking force to said motor shaft, the respective stationary indexing and braking contacts being arranged with respect to said rotor shaft to contemporaneously deenergize the selected motor-energizing circuit and to energize the corresponding motor braking circuit to selectively position the rotor at the first and second stations, and switch means having contacts in said motor braking circuit maintained closed by continuous rotation of said motor shaft in the forward direction and opening upon reverse movement of said motor shaft, said switch means comprising a member frictionally connected with said motor shaft to tend to rotate therewith, a switch actuated by movement of said member thereagainst as the motor shaft is rotated in the forward direction, but opened as the member moves with the shaft in the reverse direction, and selector means for selectively accommodating energization of said first motor energizing and motor braking circuits and said second motor energizing and motor braking circuits.
